UNITED STATES PATENT OFFICE.

EARL H. ARMES, OF JULESBURG, COLORADO.

AIR-COOLING SYSTEM.

1,390,862.

Specification of Letters Patent. Patented Sept. 13, 1921.

Application filed December 24, 1919. Serial No. 347,287.

To all whom it may concern:

Be it known that I, EARL H. ARMES, a citizen of the United States, residing at Julesburg, in the county of Sedgwick and State of Colorado, have invented certain new and useful Improvements in an Air-Cooling System, of which the following is a specification.

The invention relates to an air cooling system and more particularly to the class of motor cooling systems for internal combustion engines employed in automobiles.

The primary object of the invention is the provision of a cooling apparatus of this character wherein the cylinders and adjunct parts of an internal combustion engine will be cooled by circulating currents of air admitted at the front of an automobile and directed about the cylinders of the engine, the apparatus being constructed to supply air about the respective cylinders independently of each other and the admitted air being drawn off through the medium of a suction fan, thereby to avoid excess heating thereof during the working of the same.

Another object of the invention is the provision of an apparatus of this character the construction of which is novel in form so that it can be applied to an internal combustion engine employed in automobiles without necessitating any material changes or alterations in the construction of the engine and when so applied will effect the circulation of air about the cylinders thereof in a unique manner so that all danger of freezing in cold weather is eliminated, as the use of the usual water jackets about the cylinders of the engine are entirely dispensed with.

A further object of the invention is the provision of an apparatus of this character the air inlet of which is of novel construction to admit air currents independently of each other into the housing or casing about the cylinders of an internal combustion engine so that individual currents of air will circulate about the respective cylinders and thereafter be drawn off to avoid the heating of the air, thus maintaining the engine cool at all times, the air being admitted constantly about the engine while in operation.

A still further object of the invention is the provision of an apparatus of this character which is comparatively simple in construction, thoroughly reliable and efficient in

operation and inexpensive to manufacture and install.

With these and other objects in view, the invention consists in the features of construction, combination and arrangement of parts as will be hereinafter fully described, illustrated in the accompanying drawing and pointed out in the claims hereunto appended.

In the accompanying drawing,—

Figure 1 is a view partly in side elevation and partly in section showing the cooling apparatus constructed in accordance with the invention in its applied relation to the internal combustion engine of a motor vehicle.

Fig. 2 is a top plan view of the cooling apparatus, a portion of the jacket for the cylinders of the engine being broken away and likewise the point of connection of the fan with the exhaust pipe being shown in section.

Fig. 3 is a vertical transverse sectional view through the suction fan.

Fig. 4 is a plan view of one of the fan blades.

Similar reference characters indicate corresponding parts throughout the several views in the drawing.

Referring to the drawing in detail, A designates one of the cylinders of a multiple cylinder combustion engine which is conventionally shown and mounted in the usual manner under the hood of a motor vehicle, the latter being designated generally at B and is of any ordinary well known construction.

At the front end of the hood of the motor vehicle B, as a substitute for the usual water radiator, is positioned the inlet mouth 5 of the air cooling apparatus, which comprises a housing or jacket 6 of a size and shape to fit over the cylinders A of the motor, the size of the housing or jacket 6 being such as to provide an air circulating space 7 entirely about the vertical walls and heads of the cylinders of the engine and this housing or jacket is fixed to the base of the engine or chassis of the automobile B in any suitable manner.

Superposed relative to the housing or jacket 6 longitudinally thereof and approximately centrally of the same is a rearwardly tapered air conduit 8 which terminates in a forward flared portion 9 formed with the entrance mouth 5, which latter is provided with a reticulated or wire mesh front 10.

while the rear or smaller end of said conduit 8 is formed with an elbow 11 constituting a connecting neck 12 tapped or otherwise engaged in the top of the housing or jacket 6 and serving as an inlet to one of the cylinders of the engine. Arranged in the interior of the conduit are vertical and transverse dividing walls or partitions 13 and 14 respectively, which terminate as shown by 10 dotted lines in Figs. 1 and 2 of the drawing, thereby dividing the conduit into plural passages, according to the number of cylinders of the engine, and leading from these passages are the connecting tubes 15 which are 15 tapped or otherwise engaged in the top of the housing or jacket 6 for directing independent air currents flowing through the respective passages and connecting tubes 15 to the other cylinders of the engine so that 20 these cylinders will receive separate air currents independently of each other, the air being admitted through the intake mouth 5 of the conduit 8 as will be apparent.

Arranged at one side of the housing or 25 jacket 6 is a hot air manifold 16 having the terminal branches 17 tapped or otherwise engaged with the jacket 6 for the communication of said hot air manifold 16 with the air spaces formed by the housing or jacket 30 6 about the respective cylinders of the engine, the manifold 16 being held secure by brackets 18 and connected immediately with this manifold is an outlet pipe 19 suitably secured in place by the cleats 20 carried by 35 the housing or jacket 6, the pipes 19 being directed forwardly and connected at its free end with the hollow hub 21 of a suction fan 22 journaled in supports 23 and 24 respectively, the fan 22 being formed with dual 40 series of blades 25 and 26 respectively, one of the blades 26 being shown in detail in Fig. 4 of the drawing and these blades 25 and 26 are radially arranged in the fan wheel 22 for the drawing of the hot air from the 45 manifold 16, through pipe 19 and exhausting it at the periphery of the fan wheel, the hot air being drawn in the fans centrally of the same. Motion is imparted to the fan 22 through the medium of a sprocket 50 chain 27 which is driven from a countershaft 28, geared at 29 to the power shaft 30 of the engine, it being understood of course that it is preferable to inclose the gearing 29 and other driven parts between the engine 55 and the fan and to lubricate the same automatically in any suitable manner.

In the operation of the apparatus atmospheric air is admitted through the mouth 5 of the conduit 8, thence conveyed through 60 the neck 12 and tubes 15 into the jacket or housing 6 for circulation in the air spaces 7 about the cylinders A of the engine, the hot air being drawn off through the manifold 16, pipe 19 and suction fan 22, thereby 65 maintaining the engine cool at all times and

eliminating all danger of freezing in cold weather as the usual water cooling system is entirely dispensed with. By reason of the construction and the employment of the air cooling apparatus a considerable saving in 70 the consumption of gas for the working of the engine is had and the perfect working thereof is assured.

From the foregoing it is thought that the construction and manner of operation of the 75 apparatus will be clearly understood and a more extended explanation has been omitted.

What is claimed is:

1. The combination with an internal combustion engine having multiple cylinders 80 and a hood of an automobile open at its front, of an air cooling apparatus comprising a jacket covering the cylinders of the engine and divided into separate chambers for the respective cylinders and forming air 85 circulating spaces about said cylinders, a longitudinally, rearwardly tapered air conduit superposed relative to the jacket and having independent air passages communicating with the respective chambers of the 90 jacket at the location of the respective cylinders, a reticulated flared intake mouth on the conduit and arranged in the open end of the hood, and suction means for drawing off hot air from the jacket and operated by 95 the engine.

2. The combination with an internal combustion engine having multiple cylinders and a hood of an automobile open at its front, of an air cooling apparatus comprising 100 a jacket divided into chambers covering the respective cylinders of the engine and forming air circulating spaces about said cylinders, a longitudinal, tapered air conduit superposed relative to the jacket and having 105 independent air passages communicating with the respective chambers of the jacket at the location of the respective cylinders, a reticulated flared intake mouth on the conduit and arranged in the open end of the 110 hood, a hot air manifold having branches connected with the respective chambers of the jacket for communication therewith at the top of the respective cylinders of the engine, an outlet pipe leading from the manifold, and a suction fan having a hollow hub 115 connected with the outlet pipe for exhausting air therefrom by the fan when active.

3. The combination with an internal combustion engine having multiple cylinders 120 and a hood of an automobile open at its front, of an air cooling apparatus comprising a jacket covering the cylinders of the engine and divided into chambers to inclose the respective cylinders and forming air 125 circulating spaces about said cylinders, a rearwardly directed, tapered air conduit superposed relative to the jacket and having independent air passages communicating with the respective chambers of the jacket at the 130

top of the respective cylinders, a reticulated flared intake mouth on the conduit and arranged in the open end of the hood, a hot air manifold having branches connected with the respective chambers of the jacket for communication therewith at the location of the respective cylinders of the engine, an outlet pipe leading from the manifold, a suction fan having a hollow hub connected with the outlet pipe for exhausting air therefrom by the fan when active, and connections with the engine for operating the fan when the engine is active. In testimony whereof I affix my signature hereto.

EARL H. ARMES.
